UNITED STATES PATENT OFFICE

163,874

CIGAR LIGHTER OR SIMILAR ARTICLE

Frederick Kaupmann, Brooklyn, N. Y., assignor to Ronson Art Metal Works, Inc., Newark, N. J., a corporation of New Jersey

Application August 22, 1950, Serial No. 11,878

Term of patent 14 years

(Cl. D48—27)

To all whom it may concern:

Be it known that I, Frederick Kaupmann, a citizen of the United States, residing in Brooklyn, in the county of Kings and State of New York, have invented a new, original, and ornamental Design for a Cigar Lighter or Similar Article, of which the following is a specification, reference being had to the accompanying drawing, forming part thereof, in which,

Fig. 1 is a side elevation of a lighter or similar article embodying my new design, the characteristic features of the design being shown in full lines;

Fig. 2 is an end elevation thereof, looking toward the right of Fig. 1; and

Fig. 3 is a top plan view thereof.

I claim:

The ornamental design for a cigar lighter or similar article, substantially as shown and described.

FREDERICK KAUPMANN.
